L. N. D. WILLIAMS,
DEVICE FOR TRANSFERRING AND DOUBLING KNITTED WEBS,
APPLICATION FILED JAN. 22, 1918.

1,348,195.

Patented Aug. 3, 1920.

INVENTOR LOUIS N. O. WILLIAMS

BY HIS ATTORNEY Harry Smith

UNITED STATES PATENT OFFICE.

LOUIS N. D. WILLIAMS, OF OGONTZ, PENNSYLVANIA.

DEVICE FOR TRANSFERRING AND DOUBLING KNITTED WEBS.

1,348,195.

Specification of Letters Patent.

Patented Aug. 3, 1920.

Application filed January 22, 1918. Serial No. 213,197.

To all whom it may concern:

Be it known that I, Louis N. D. Williams, a citizen of the United States, residing in Ogontz, Pennsylvania, have invented 5 certain Improvements in Devices for Transferring and Doubling Knitted Webs, of which the following is a specification.

My invention consists of certain improvements in or additions to the stitch transferring and doubling device shown in the 10 Letters Patent No. 1,068,853, granted July 29, 1913, to myself and Walter D. Butz as assignees of said Walter D. Butz, one object of my present invention being to so mount 15 the hinges of the point carriers as to maintain the proper relation between the axes of the hinges and the tips of the stitch-receiving points; a further object being to arrest, at the proper time, the swinging of 20 one set of points over the other so as to dispose the points tip to tip; and other objects being to insure the doubling of the stitches upon the proper set of transfer points, and to prevent accidental release of 25 the stitches from the points after the stitches have been applied to said points.

Some of the features of my present invention are also applicable to stitch transferring devices generally, whether or not the 30 stitches are afterward doubled.

In the accompanying drawing

Figure 1 is a bottom view of a stitch transferring and doubling device constructed in accordance with my present invention, showing the parts in the positions assumed by them when stitches are being transferred to the points of the device from the needles of a knitting machine;

Fig. 2 is a view partly in elevation and 40 partly in vertical section on the line 2—2, Fig. 1;

Fig. 3 is a view of part of one of the point carriers looking toward the inner face of the same;

Fig. 4 is an outside view showing some of the points, at one terminal of each set, when the said points are in position for receiving stitches from the needles of the knitting machine;

Fig. 5 is a similar view showing the relation to each other of the same points when adjusted to position for transferring stitches from one set of points to the other;

Fig. 6 is an enlarged sectional view 55 through one of the point carriers and one of

the stripper plates, illustrating the duplex character of the stitch-receiving points of each set, and

Fig. 7 is a side elevation of portions of the hinge plates showing the relation of said 60 hinge plates to one another when one of the point carriers has been turned over the other so as to adjust the stitch-receiving points to the position shown in Fig. 5.

In Fig. 2 of the drawing the points which 65 normally would be shown in the distance have been omitted in order to prevent confusion, the planes of the tips of the points being indicated by dot and dash lines.

In the drawing I have shown the stitch-transferring and doubling device as constructed for use in connection with a circular knitting machine, the point carriers 1, 1^a, being each of semi-circular form with semi-circular sets of points projecting longitudinally therefrom, but it should be understood that in constructing the transferring and doubling device for use in connection with a machine having straight needle beds the point carriers will consist of straight 70 bars corresponding to the straight bars of the knitting machine and having straight rows of stitch-receiving points for registering with the straight rows of needles carried by said needle bars.

Instead of the single points shown in the patented device, the points are now disposed in pairs, one of the pair, (indicated at 3, in Figs. 2 and 6) being on the outside and the other, (indicated at 3^a in said figures) being 75 on the inside, so that, in transferring stitches from needles of the knitting machine to said points, the point 3 will pass through a stitch of one course and the point 3^a through a stitch of the preceding course, the latter stitch being clamped between the 80 inner and outer points so as to prevent accidental detachment of the web from the points during the manipulation of the device subsequent to the transfer operation.

In order to render the stitch-engaging end of the inner point 3^a properly elastic, said point is recessed on its outer face, as shown in Figs. 2 and 6, thus providing an elastic connection between the outer portion of the 105 point and the shank of the same, and to permit inward yielding movement of the elastic end of the point 3^a, that face of the transferring 13 (hereinafter referred to) which may be adjacent to the point, is beveled.

110

Each point carrier is composed of members 4, 4^a between which the shanks of the points 3, 3^a are rigidly confined, the members 4, 4^a being retained in their proper 5 confining relation to one another by any suitable means.

The point carriers 1, 1^a, are hinged together by means of opposite pairs of hinge plates 5, 5^a, located inside of the circumferential plane of the points, one of each pair of hinge plates being secured to its appropriate carrier, and the hinge pintles 6 being so located that their axes are substantially in line longitudinally with the tips of 10 the points 3 and midway between the terminal points of the two sets, as shown by the dot in Figs. 4 and 5. In order to provide for the convenient adjustment of the hinge plates so as to properly locate the axes 15 of the hinge pintles, said plates are provided with slots 7 for the reception of securing bolts or screws 8 which are carried by blocks 9 mounted so as to be adjustable from and toward each other on internally projecting 20 flanges 10 on the point carriers 1 and 1^a, as shown in Figs. 1 and 2, provision being thus afforded for adjusting the hinge plates 5, 5^a both longitudinally and circumferentially and thereby effecting corresponding adjustment 25 of the axes of the hinge pintles in respect to the stitch-receiving points, movement of the hinge plates in either direction having no effect upon their rigid retention in the opposite direction.

30 In order to prevent forcible contact of the tips of the points when one set has been turned over so as to point toward the other set, as in Fig. 5, each hinge plate 5 has a shoulder 11 formed upon it, and the other plate 5^a carries a stop finger 12, as shown 35 in Figs. 2 and 7, whereby, when one point carrier is turned over the other, in order to bring the points into the relation with each other shown in Fig. 5, the stop plate 12 will 40 contact with the shoulder 11, as shown in 45 Fig. 7, so as to prevent further swinging movement of one carrier in respect to the other in that direction, thereby arresting the points with their tips approaching or 50 barely in contact with one another, as shown in Fig. 5. Bearing against the members 4^a of the point carriers 1, 1^a, are stripper plates 55 13, 13^a, with teeth 14 projecting between the successive pairs of points, 3, 3^a, hence, by 60 moving either plate away from the member 4^a of the point carrier, the stitches will be stripped from the points 3, 3^a of said carrier.

Each of the stripper plates 13, 13^a has a 65 pair of rods 15 passing through and guided in suitable openings in the members 4, 4^a of the corresponding point carrier, and each of these pairs of rods carries, at the inner ends of the rods, a presser plate 16 or 16^a, which, 70 when pressed upon by the thumb or finger,

causes the desired stripping movement to be imparted to the corresponding stripper plate.

When transferring stitches from one set of points to the other the stitches are 70 stripped from the points of one set and doubled with the stitches already upon the corresponding points of the other set, and, in order that this stripping movement may always be effected in connection with one 75 and the same set of points, the presser plate 16 is provided with a locking lever 17 which engages a notch 18 in the outer flange or rim 19 of the point carrier 1, as shown in Figs. 1 and 2. Projection of the stripper plate 80 13 is therefore normally prevented, and the normal transfer of stitches is from the points of the carrier 1^a to those of the carrier 1. In order, however, to permit stripping of the 85 stitches from the points of the carrier 1, when desired, the lever 17 is pivotally mounted, and can, therefore, be readily withdrawn from engagement with the notched portion of the rim 19 when desired.

When the stitches have been doubled upon 90 the points of the carrier 1, the carrier 1^a may be turned back to its normal position, as shown in Figs. 1 and 2, and the device may then be applied to the intermittently moved member of an ordinary looping machine whereby the successive pairs of 95 stitches are presented successively to the needles or other looping devices of said machine, whether said stitches remain upon the points 1, or are transferred therefrom to 100 corresponding points of the looping machine.

As the looping devices always bear a fixed circumferential relation to the member of the looping machine upon which the point carrier is mounted, it is advisable to provide means for circumferentially adjusting said point carrier so that the looping device will properly register with the stitch-carrying points, and for this purpose I provide 110 said point carrier with a projecting pin 20, for engaging a vertical slot in the intermittently movable member of the looping machine, said pin 20 projecting through a slot 22 in the rim 19 of the point carrier, and being carried by a plate 21 which is adjustable circumferentially upon the inner face 115 of said rim 19, as shown in Figs. 1 and 3.

I claim:

1. In a device for doubling the stitches of a knitted web, the combination of two sets of stitch-receiving points, a carrier for each set, and a hinge for connecting said carriers so that one may be folded over the other, said hinge comprising laterally adjustable blocks and hinge plates adjustable longitudinally on said blocks, whereby either adjustment can be effected independently of and without affecting the other.
2. In a device for doubling the stitches 130

of knitted webs, the combination of two sets of stitch-receiving points, a carrier for each set, said carriers being so supported that one can be folded over the other, and a plate 5 for stripping stitches from one set of points and applying them to the other, said stripper plate having rods guided in and projecting longitudinally beyond the point carrier, and a segmental presser plate mounted 10 upon the inner ends of said rods.

3. In a stitch-transferring device for knitted webs, the combination of a point carrier, with duplex stitch-receiving points, one inwardly beyond the other and having 15 transversely separated ends, whereby a stitch, applied longitudinally to an inner point, will as it is moved along the point

to which it has been applied be clamped between the same and the outer point.

4. In a stitch-transferring device for 20 knitted webs, the combination of a point carrier with duplex stitch-receiving points, one inwardly beyond the other and having transversely separated ends, whereby a stitch, applied longitudinally to an inner 25 point, will as it is moved along the point to which it has been applied be clamped between the same and the outer point, one of said points being recessed inwardly from its outer end so as to increase the elasticity 30 of the portion outwardly beyond the recess.

In testimony whereof I have signed my name to this specification.

LOUIS N. D. WILLIAMS.
